UNITED STATES PATENT OFFICE.

WINSLOW S. LINCOLN, OF WORCESTER, MASSACHUSETTS.

OPERATING AND LATCH-RELEASING MECHANISM FOR SLIDING DOORS.

SPECIFICATION forming part of Letters Patent No. 700,343, dated May 20, 1902.

Application filed February 27, 1901. Serial No. 49,097. (No model.)

To all whom it may concern:

Be it known that I, WINSLOW S. LINCOLN, a citizen of the United States, residing at Worcester, in the county of Worcester and 5 State of Massachusetts, have invented a new and useful Operating and Latch-Releasing Mechanism for Sliding Doors, of which the following is a specification.

This invention relates to an operating and 10 latch-releasing mechanism for sliding doors which has been primarily designed for use in connection with the sliding doors of street-cars and which may also be used to advantage in other situations. 15 The especial object of this invention is to provide a special form of construction for fastening and releasing sliding doors, so that when a door is in its locked position it may be unlocked and drawn open by a straight pull 20 upon the door-handle.

My construction has been especially designed for use on street-car doors, although it may be used to advantage in other locations.

To these ends my invention consists of the 25 parts and combinations of parts, as hereinafter described, and more particularly pointed out in the claims at the end of this specification.

In the accompanying drawings, Figure 1 is 30 a fragmentary perspective view illustrating the application of an operating and latch-releasing mechanism constructed according to my invention to a sliding door and to the casing thereof. Fig. 2 is an enlarged transverse 35 sectional view of the sliding door and its latch-releasing mechanism. Fig. 3 is a sectional view illustrating the position of the parts when the door is in its locked or closed position, and Fig. 4 is a fragmentary perspective view of the parts which are mounted in the sliding door.

In order to provide a satisfactory door-catch and operating connection for the doors of street-cars or for use in similar locations, it is 45 essential to provide a construction by means of which the door will be securely locked or held in its closed position and by means of which the door can immediately be slid open without requiring a separate operation for releasing or lifting the door-latch. To provide 50 a construction for accomplishing these results, an operating and latch-releasing mech-

anism for sliding doors constructed according to my invention comprises an operating-handle and a latch-releasing mechanism 55 mounted in the door and a latch or catch, which is mounted in the door-casing, said parts being arranged so that when the operating-handle is pulled to open the door the releaser will disengage the latch, after which 60 the door may be drawn open. Two operating-handles are preferably employed, so that the door can be opened or closed either from the inside or from the outside.

Referring to the accompanying drawings 65 and in detail, A designates a portion of a sliding door of any ordinary or approved construction, and B designates a portion of the door-casing. Screwed onto or otherwise secured to the door A are brackets 10, and pivotally mounted on screws 14 in the brackets 10 are the operating-handles 11. The upper arm or branch of each operating-handle 11 is provided with a tongue or projection 12, as illustrated most clearly in Fig. 4, while the 70 lower arm or part 13 of each handle 11 may form stops for limiting the extent to which the operating-handle can pivot or turn on its screws 14.

Mortised or set into the door A is a socket- 80 section 15, (illustrated most clearly in Fig. 4,) having a face-plate 16 for receiving screws to hold the same in place. Mounted to slide or move longitudinally in the socket-piece 15, as illustrated most clearly in Fig. 3, is a latch- 85 releaser or cam-piece 17, having an inclined front face and having a notch near its rear end for the tongues or projections 12, extending in from the handles 11.

The latch or catch, which is mounted in the 90 door-casing, may be of substantially the ordinary construction, and, as herein illustrated, the latch or catch 20 may be pivoted in a casting 18, having a face-plate 19 for receiving the screws which hold the same in place in the 95 door-casing.

In the use of an operating and latch-releasing mechanism as thus constructed when the door is pulled together or closed by means of one of its operating-handles 11 the parts will 100 occupy the position illustrated in Fig. 3 and the latch 20 will lock the door in its closed or shut position, and when either of the operating-handles is pulled to open the door the

latch-releaser 17 will first be slid forward to release the latch or catch 20, so that the door will then be drawn open without requiring a separate operation for releasing the latch.

5 I am aware that numerous changes may be made in applying my invention to sliding doors by those who are skilled in the art. For example, a single operating-handle may be employed in places where it is desired to 10 operate and unlock the door from one side only. I do not wish, therefore, to be limited to the construction I have herein shown and described; but

15 What I do claim, and desire to secure by Letters Patent of the United States, is—

1. In an operating and latch-releasing mechanism for sliding doors, the combination of an operating-handle pivotally mounted upon the sliding door, a sliding cam-piece or latch-releaser mounted in the sliding door and connected to be moved by the operating-handle, and a latch pivotally mounted in the door-casing, said parts being arranged so that when the operating-handle is pulled to open the 20 door, the releaser will first disengage the latch, after which the door may be drawn open, substantially as described.

2. In an operating and latch-releasing mechanism for sliding doors, the combination of a 25 latch-socket mounted in the door, a sliding inclined-ended latch releaser or bolt, two operating-handles pivotally mounted on opposite sides of the sliding door and connected to

move the latch-releaser, and a latch pivotally mounted in the door-casing in position to engage the latch-socket, said parts being arranged so that when either operating-handle is pulled to open the door, the releaser will first disengage the latch from its socket, after which the door may be drawn open, substantially as described.

3. In an operating and latch-releasing mechanism for sliding doors, the combination of a latch socket-piece mortised into a sliding door, and having a face-plate for receiving 45 screws to hold the same in place, a sliding latch-releaser mounted in the latch socket-piece, operating-handles pivoted in brackets upon opposite sides of the door and having inwardly-projecting fingers engaging a notch 50 in the latch-releaser, and a gravity-latch mounted in a pivot-piece which is mortised into the door-casing and which is provided with a face-plate for receiving the screws for holding the same in place, said parts being arranged so that when either operating-handle is pulled to open the door, the releaser will first disengage the latch, after which the door may be drawn open, substantially as described.

55 In testimony whereof I have hereunto set 60 my hand in the presence of two subscribing witnesses.

WINSLOW S. LINCOLN.
